UNITED STATES PATENT OFFICE

EMANUEL MOOR, OF MONT PELERIN SUR VEVEY, SWITZERLAND

KEYBOARD FOR MUSICAL INSTRUMENTS

Application filed January 29, 1930, Serial No. 424,419, and in Germany March 9, 1928.

This invention has reference to that kind of key boards for musical instruments in which rows of keys are arranged one behind or to the rear of each other, instead of being disposed in one single row. Such an arrangement has been suggested heretofore mainly for the purpose of facilitating the playing of octaves or of other multiple accords necessitating the manipulation of several, comparatively widely spaced keys which it is difficult to strike and to uniformly actuate by persons having small or untrained hands or short finger-links. It has already been proposed to improve the construction of the key boards referred to by somewhat inclining the front row, so as to shorten the distance between the key boards, but even with this arrangement it was impossible to arrive at the most favorable position of the hands of the player, particularly when a rapid change of position of the hand between very distant points of the strokes to be effected upon the parallel key boards or parts thereof becomes necessary, and the playing operation is thereby interfered with in view of the fact that with the arrangements referred to unnatural twisting and stretching of the hands or fingers is required in the case of small or short hands or finger links. An increase of the striking force of the fingers upon the keys in the operation of the duplicate key-boards referred to can only be obtained by changing the angle of incidence of the striking force of the fingers with relation to the keys. However, this object cannot be accomplished by an increase of the inclination of one row of keys only, inasmuch as by this means the effort of lowering the fingers and striking the keys is increased and the rapid inspection of the keyboard is greatly interfered with.

Now, in accordance with my invention the accessibility and the convenience and facility of operation of the keys, as well as the uniformity of stroke of the fingers, particularly in the case of multichord sounds is highly improved by causing the key boards to form a kind of dihedral angle, so as to arrange the rear keys at an incline towards

the horizontal in a descending plane, while the front keys are arranged at an ascending angle with relation to the player.

My invention is illustrated by way of exemplification on the accompanying drawing in longitudinal section in connection with a double piano key board of the kind referred to. The key board confronting the player is formed by the white keys *h* and the black keys *i* the striking surfaces of these keys being inclined with relation to the horizontal and ascending towards the player. The rear key board comprises the rows *k* and *l* and has striking surfaces which descend in the direction of the player. By means of this arrangement the most favorable and hygienically most unobjectionable position is obtained as regards the playing hand and the erect position of the body of the operator as regards the simultaneous playing on both key boards and for the purpose of a rapid, suddenly changing, jumping alternate operation of the key boards. The manipulation may be further facilitated by providing height increasing blocks *e* or enlargements upon the front white keys between the corresponding black keys for the purpose of providing a uniform, substantially unbroken plane for the rear operating surface of the front keys.

The manner of journaling the keys has not been shown, as it is immaterial for this invention and forms no part thereof. The keys may be supported in the usual manner by supporting bars and guide pins.

The inclined position described of the striking surfaces may be obtained by the inclined arrangement of the entire key or of part thereof, particularly of the front portion, or even by a corresponding configuration of the striking surface alone. I also wish it to be understood that my invention is not restricted to the particular embodiment herein shown merely by way of illustration of its principles, and that modifications are possible within the ambit of the appended claims.

I claim:—

1. Multichord musical key board comprising rows of keys disposed one to the rear of

the other, and inclined towards each other so as to constitute the sides of a dihedral angle.

2. Multichord musical key board, comprising front rows of keys inclined towards the horizontal and ascending towards the player and rear rows of keys inclined towards the horizontal and descending towards the player.
